[57] ABSTRACT

A sliver guide is illustrated having a substantially U-shaped bracket defining an opening therein for receiving a flat bar cradle shelf in clamping engagement, a pair of transversely spaced standards are carried by the bracket extending upwardly therefrom, a pair of opposed inner converging surfaces each carried by a respective standard, condense and guide sliver into an entrance nip between apron members, and the standards define an opening at the top therebetween for receiving a sliver laid therein.

therein for receiving the flat bar or cradle shelf 27 therebetween in clamping engagement. The bracket is preferably constructed of molded somewhat flexible plastic, such as nylon, and the legs 28 and 29 are slightly biased towards each other so that the flat bar is received therebetween in resilient clamping engagement.

The sliver guide is preferably molded entirely of suitable plastic, and carries a pair of transversely spaced standards B extending upwardly therefrom. The standards B are essentially in the form of posts but the inner surfaces thereof converge, as illustrated at C, and such converging surfaces guide and contains the sliver controlling the fibers thereof, immediately prior to their entrance into the nip between the apron members 18 and 19.

As has been previously pointed out, the standards define an opening D at the top therebetween for receiving a sliver S when laid in by the operator. During the opening operation, when the end comes down the operator twists the end for insertion into the trumpet 17 and after the strand passes through the nip formed by the back bottom roll and the back top roll it is laid by the operator between the standards B of the sliver guide. It is evident that the sliver guide requires no adjustment and readily permits replacement by another sliver guide affording an indicated different spacing between the standards B. Thus a variety of sliver weights may be accommodated by simply changing the sliver guides. Since a separate unitary sliver guide is provided for each delivery, there is no problem of adjustment and replacement is easily accomplished when indicated.

While a preferred embodiment of the invention has been described using specific terms, such description is for illustrative purposes only, and it is to be understood that changes and variations may be made without departing from the spirit or scope of the following claims.

What is claimed is:

1. For use in a top roll cradle having a flat bar carried between a pair of spaced side members which support a pair of opposed apron members having an entrance nip defined by an entrance between said apron members, said bar being positioned above and closely adjacent said entrance nip, a sliver guide comprising a substantially U-shaped bracket, a pair of transversely spaced standards carried by said bracket extending upwardly therefrom, a pair of opposed inner converging surfaces each carried by a respective standard condensing and guiding a sliver into the entrance nip between the apron members, said guide being constructed of molded flexible plastic, said bracket having opposed, 15 inner flat surfaces defining an opening therein for receiving said flat bar, said flat surfaces resiliently biased toward each other so that said bar is received therebetween in resilient frictional clamping engagement, and said standards defining an opening at the top therebetween for receiving said sliver laid therein, whereby the guides may be easily replaced when damaged or when a different size is indicated.
2. The structure set forth in claim 1 wherein said bar is disposed in a plane substantially parallel to the path 20 of travel of fibers into said entrance nip between said apron members.
